DRILL PRESS SPEED REDUCING ASSEMBLY

Stefan Kafka, Cicero, III.

Application April 15, 1949, Serial No. 87,699

6 Claims. (Cl. 74—217)

1

This invention relates to improvements in attachments for machines for performing boring and drilling operations, such as a drill press, and it has particular reference to a device for use with a conventional type of drill press operating by belt drive from an electric motor whereby the range of speed may be materially increased to include a comparatively low speed

It is an object of this invention to provide an attachment of this character which will enable conventional belt driven drill presses to be operated at a speed sufficiently low to perform work with larger sized tools and at the same time avoid damage to such tools by overheating and other conditions which arise when high speed work is undertaken with such tools.

Another object of this invention is to provide a drill press attachment which is not only economical to manufacture, but which is easy to apply to a drill press, and also very compact and highly efficient and reliable in use.

The present invention consists of the combination and arrangement of a drill press having an upright column and a drill head on said column, a driving motor having a driving pulley and a drill spindle having a driven spindle, said driving pulley being connected to said driven pulley by means of a pair of intermediate pulleys, each of said intermediate pulleys being supported on said column for rotation about an axis in spaced parallel relation to the axis of the other intermediate pulley and in spaced parallel relation to the axis of the driving and driven pulleys.

All of the foregoing and still further objects and advantages of the invention will become apparent from a study of the following specification, taken in connection with the accompanying drawings wherein like characters of reference designate corresponding parts throughout the several views, and wherein:

Fig. 1 is a perspective view of the drill head and column of a conventional drill press showing a speed reducing attachment secured to said column in accordance with the present invention.

Fig. 2 is an enlarged plan view of the device as shown in Fig. 1.

Fig. 3 is an enlarged vertical section taken on line 3-3 of Fig. 2.

Fig. 4 is a perspective view similar to Fig. 1, showing a modified form of speed reducing attachment for use on a drill press requiring mounting of the intermediate pulleys to one side of the drill head.

2

Fig. 5 is a top plan view of the device as shown in Fig. 4.

Fig. 6 is a fragmentary enlarged vertical section taken on line 6-6 of Fig. 5.

5. Reference being had more particularly to the drawings, the numeral 10 indicates the drill press head supported on the vertical column 11 of a conventional form of drill press. Axially slidably within the head 10 under control of a handle 12 is a quill 13, and rotatably mounted within the quill 13 is a spindle 14 having a chuck 15 at its lower end for the reception of the shank of a suitable tool 16. The table for supporting articles of work to be operated upon by the tool 16 is designated by the reference number 17.

Power for rotating the spindle 14 is provided by an electric motor 18 supported on a bracket 19 fastened to the head 10 having belt drive connection between a pulley 20 on the motor shaft 21 and a pulley 22 splined to the spindle 14, each of said pulleys being of the multi-step cone type.

25 A belt drive connecting the smallest step of the motor shaft pulley 28 and the largest step of the spindle pulley 22, on the basis of a pulley speed of 1750 revolutions per minute at the shaft of a conventional $\frac{1}{4}$ horse power motor having 1750 revolutions per minute, would cause the spindle pulley to revolve at the rate of 700 revolutions per minute. Under these conditions 30 the use of tools of a size greater than $\frac{3}{8}$ " diameter would be prohibited because of the danger of overheating and damaging the tool. It is accordingly necessary to provide speed

35. reducing means between the pulleys 20 and 22. This is accomplished in accordance with the present invention, as shown in Figs. 1, 2 and 3, by means of a pair of supplementary multi-step cone pulleys, such as pulleys 25 and 26. A pair 40 of arms 27 and 28 fastened to the column 11 of the drill press, so as to project a uniform distance in opposite directions radially of the column and at right angles to a line connecting the axes of the pulleys 20 and 22, provide means 45 for supporting the pulleys 25 and 26 in spaced relation to each other and for rotation about axes in spaced relation to the axes rotation of the pulleys 20 and 22. A yoke 29 at the inner end of the arm 27 and a similar yoke 30 at the 50 inner end of the arm 28 cooperate to encircle the column 11, and aligned openings in abutting flanges of said yoke portions 29 and 30 of said arms receive bolts 31 which are tightened to clamp the arms 27 and 28 in rigid assembly with the column 11. The outer or free end of each

arm 27 and 28 is formed with an elongated slot 32 extending lengthwise of said arms. Each pulley 25 and 26 is provided with a central bearing 33 which turns on a shaft 34 having its lower end clamped in place lengthwise of said slot 32 by means of a clamping nut 35. In order to distribute lubricant to the space between the bearing and the shaft, the latter is provided with the passage 36 leading from the upper end of the shaft into a space 37 provided in the side wall of the shaft. Lubricant supplied by a cup 38 fitted to the upper end of the passage 36 is accordingly conducted to the shaft and the bearing associated with each pulley 25 and 26.

In order to establish a driving connection between the pulleys 20 and 22 via the pulleys 25 and 26, with a view to obtaining a speed reduction suitable for operation of comparatively large tools from a conventional motor 18 in accordance with the present invention, a belt 39 is trained about the smallest step of pulley 20 and the largest step of pulley 26, a belt 40 is connected from the smallest step of pulley 26 to the largest step of pulley 25 and a belt 41 is connected from the smallest step of pulley 25 to the largest step of spindle pulley 22. The speed of the spindle pulley 22 is accordingly reduced in the ratio of 15 to 1 relative to the speed of the motor pulley 20 whereby a spindle speed of 90 to 100 revolutions per minute is obtained to accommodate use of drills up to 1 inch diameter and boring tools of a size as large as 3½ inch diameter without danger of damaging the tool.

Due to variations in the design and construction of drill heads of certain types of drill presses, the clearance available about the spindle pulley is sometimes insufficient to accommodate an arrangement of belt drives as shown in Fig. 1. In connection with drill presses such as the type shown in Fig. 4, an arm 45 extending upwardly and forwardly from the head 46 to provide a bearing in upward vertical alignment with the axis of the spindle pulley 45 would interfere with a belt drive such as represented by the belt 41 shown in Fig. 2. In such a case the present invention contemplates the use of a stub column member 48 adjustably clamped in a slot 49 provided in the outer end of an arm 50, which arm is fastened to the main column 51 of the press by a clamp 52. The stub column member 48 accordingly provides a support for a pair of pulley supporting arms 53 and 54, corresponding to the pulley supporting arms 27 and 28 shown in Figs. 1 to 3 inclusive. As shown in Fig. 5 and Fig. 6, each arm 53 and 54 has a yoke portion 55 clamped to the member 48 by means of clamping bolts 56, with the arms 53 and 54 extending along a line in spaced parallel relation to a line joining the spindle pulley 47 and a pulley 57 on the shaft of the motor. A pulley 58 mounted on the arm 53 and a similar pulley 59 mounted on the arm 54 thus provide speed reducing means between the spindle pulley 47 and the motor pulley 57, with the pulleys 58 and 59 so positioned relative thereto as to accommodate a belt connection 60 between the smallest step of pulley 59 and the largest step of spindle pulley 47 without interference by the arm 45 extending from the head 46. A belt 61 connecting the smallest step of pulley 58 and the largest step of pulley 59, and a belt 62 connecting the smallest step of motor pulley 57 and the largest step of pulley 58 accordingly operate to reduce the speed of the spindle pulley 47 in the ratio of about 25 to 1 relative to the motor pulley 57. It will be noted that each of

the pulleys 47, 57, 58, and 59 is of the five step cone type and that the arm 50 connected to the main column 51 of the press is offset downwardly at the end thereof carrying the stub column member 48 whereby the steps of the supplementary pulleys 58 and 59 may be maintained in horizontal alignment with the steps of the pulleys 47 and 57.

It will be understood, of course, that the variations in the speed of the spindle, with reference to the pulleys shown in Figs. 1 to 3 inclusive as well as the pulleys shown in Figs. 4 to 6 inclusive, may be accomplished by changing the belts to different stages of the pulleys. The slots in the arms supporting said pulleys provide for any adjustment needed in the position of the pulleys to accommodate removal of the belts from one stage or step to another stage or step of the pulleys.

It is believed that the many advantages of a drill press attachment constructed in accordance with the present invention will be readily understood, and although a preferred embodiment of the device is as illustrated and described, it is to be understood that changes in the details of construction and in the combination and arrangement of parts may be resorted to which will fall within the scope of the invention as claimed.

What is claimed is:

1. In a drill press, the combination of a column, a drill head supported on said column, a drill spindle on said drill head, a motor, and means connecting the motor and said drill spindle including a multi-step pulley on said drill spindle and a multi-step pulley on the shaft of said motor, and a pair of supplementary multi-step pulleys, each of said supplementary pulleys being supported in laterally spaced relation to said drill head for rotation about an axis in spaced parallel relation to the axes of said other pulleys, a belt connecting said pair of supplementary multi-step pulleys, a belt connecting the pulley on the shaft of the motor and one of said supplementary pulleys, and a belt connecting the pulley on the spindle and the other of said supplementary pulleys.

2. In a drill press as defined in claim 1, including an arm supporting one of said supplementary pulleys and a second arm supporting the other of said supplementary pulleys, each of said arms being secured to the other in clamping relation to the column of the press.

3. In a drill press as defined in claim 1, including an arm having an elongated slotted outer end portion in which one of said supplementary pulleys is adjustably supported and a second arm having a similar slotted outer end portion in which the other of said supplementary pulleys is adjustably supported, the end of each arm remote from said slotted end being secured to the other in clamping relation to the column of the press.

4. In a drill press as defined in claim 1 including an arm secured to and projecting laterally from said column of the press, a stub column member carried by the outer end of said arm, a second arm supporting one of said supplementary pulleys, and a third arm supporting one of the other of said supplementary pulleys, said second and third arms each being secured to the other in clamping relation to said stub column member.

5. In a drill press as defined in claim 1 including an arm secured to and projecting laterally from said column of the press, said arm having its outer end offset downwardly in relation to the end thereof secured to said column of the press, a stub column member carried by the outer

end of said arm, a second arm supporting one of said supplementary pulleys, and a third arm supporting one of the other of said supplementary pulleys, said second and third arms each being secured to the other in clamping relation to said stub column member.

6. In a drill press as defined in claim 1 including an arm having an elongated slotted outer end portion in which one of said supplementary pulleys is adjustably supported and a second arm having a similar outer end portion in which the other of said supplementary pulleys is adjustably supported, the end of each arm remote from said slotted end having a yoke portion adapted to em-

brace the column of the press through an arc of substantially 180 degrees, said yoke portions being bolted, one to the other to secure said arms in clamping relation to said column of the press.
